Leo Lucken

INVENTOR

G. Carroll.
WITNESS:

BY Victor J. Evans

ATTORNEY

UNITED STATES PATENT OFFICE.

LEO LUCKEN, OF CINCINNATI, OHIO.

ARCH APPLIANCE.

Application filed October 11, 1924. Serial No. 743,077.

To all whom it may concern:

Be it known that I, LEO LUCKEN, a citizen of the United States, residing at Cincinnati, in the county of Hamilton and State of Ohio, have invented new and useful Improvements in Arch Appliances, of which the following is a specification.

This invention relates to arch appliances and is in the nature of a foot corrector in general.

The primary object of the invention is to provide a support to be worn in shoes, including low shoes, that will provide a smooth insole, and that will conform to the natural lines of the normal foot, thereby correcting a defective foot.

A further object of the invention is to provide a support that will brace the foot at its weakest point.

Other objects of the invention are to provide a support in the nature of an insole and foot corrector that is light in weight, that will not slide out of place, acts as a foot cushion as well as a support, and is simple and inexpensive to manufacture.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a perspective view of the device forming the subject matter of the present invention.

Figure 2 is a bottom plan view thereof.

Figure 3 is a view of the forms associated with the device arranged in superimposed relation for purpose of illustration.

Figure 4 is a sectional view taken on line 4-4 of Figure 1.

Referring to the drawings in detail the reference numeral 1 indicates the body portion of the device which is in the nature of an insole shaped to conform to the sole of a shoe for a normal shaped foot. The body portion has secured at its edges through the medium of stitches a base 2 which has its front edge 3 terminating beyond the central portion of the body and at the part where

the ball of the foot will rest. The end 3 is not stitched to the body but is held associated therewith through the medium of a circular anterior arch pad 4 which is stitched to the body 1 and the base as at 5. 60

The body portion 1 as well as the base 2 has laterally extending therefrom cooperating curved arch engaging pieces 6 and 7 and it is at this portion of the device that the inserts 8, 9 and 10 are arranged between 65 the base and body portion to provide the arch supporting means as shown. These inserts can be used in any number desired; in other words all of them may be used or only one as the occasion requires, depending of 70 course upon the correction necessary for the patient and the advancement of the correction. The inserts to function to an advantage must be substantially horse hoof shaped and crescent shaped as clearly shown in 75 Figure 3 of the drawings and are arranged in superimposed relation for the purpose intended. The arch supporting means is further reinforced and built up by securing the bridge pad 11 at the juncture of the arch 80 engaging pieces with the base. This bridge pad 11 may be secured at the place desirable to properly correct abnormal feet.

From the drawings and above description it will be readily apparent that the function 85 of the device forming the subject matter of the present invention is to correctly balance the weight of the body, arrange the foot in normal position thereby permitting nature to strengthen the muscles and ligaments 90 when walking and to provide proper fitting of a shoe when it does not permit proper balancing of the weight of the body.

It is thought from the foregoing description that the advantages and novel features 95 of my invention will be readily apparent.

I desire it to be understood that I may make changes in the construction and in the combination and arrangement of the several parts, provided that such changes fall within 100 the scope of the appended claims.

What I claim is:

1. A foot correcting form comprising a body, a base secured to the outer edges thereof and terminating in a free end at the longitudinally central portion thereof, a pad secured to the base and body respectively and bridging the free end of the base, and an arch supporting means associated with the body and base, 105 110

2. A foot correcting form comprising a body, a base secured to the outer edges thereof, projections laterally extending from the base and body in a manner to engage the arch of the foot, a plurality of inserts arranged between the base and body and extending between the projections, said inserts

being horse hoof and crescent shaped, and a bridge pad secured to the projection of the base to substantially brace the projections and inserts therebetween.

In testimony whereof I affix my signature.

LEO LUCKEN.
